CLAIM

The ornamental design for a shoe upper, as shown and described.

DESCRIPTION

FIG. 1 is a front perspective view of a shoe upper showing my new design;

FIG. 2 is a second front perspective view thereof;

FIG. 3 is a side view thereof;

FIG. 4 is an opposite side view thereof; and,

FIG. 5 is a top view thereof.

The broken lines immediately adjacent to the shaded area define the bounds of the claimed design, and form no part thereof. The broken lines showing the remainder of the shoe are for environmental purposes only and form no part of the claimed design.
